PITCHER'S CONTROL TARGET WITH
AUTOMATIC BALL RETURN

Hugh Mulcahy, Beaver, Pa.

Application September 4, 1951, Serial No. 244,930

3 Claims. (Cl. 273—103)

1

The present invention relates to a pitcher's control target with automatic ball return and it consists in the combinations, constructions and arrangements of parts herein described and claimed.

It is a well known fact that pitchers on baseball teams greatly outnumber catchers. Hence, many pitchers do not receive the practice they should have and catchers are usually very busy prior to a game in the catching of batting practice, hitting and warming up pitchers for batting practice. Usually there are several pitchers who need practice but who have to wait until a catcher is available and, even then, do not receive the full time they need. The present invention is such that it is available at all times and its use can easily be regulated by the manager or coach who may assign its use for given lengths of time to certain pitchers. In certain ball parks where space is available, the machine may be set up in the "bullpen," thus freeing a catcher who then may be available on the bench in case he is needed as a "pinch hitter" or replacement. The use of the present device will thus not only make an extra man available on the bench during a ball game but would help to speed up the game itself. The device consists, generally, of a target at which the practicing pitcher may throw a ball and which target is provided with openings at the "corners," that is to say at the batter's weakness points in each corner of that portion of the area above "home plate" where a "strike" may be thrown. In any event, balls which are thrown at the target and whether or not they pass through the "weakness points" will eventually come to rest upon an especially tilted platform which will deliver the thrown balls eventually to a trough where a gateway will hold the same against further movement by gravity. The gateway descends under certain circumstances to allow the ball to pass to a throwing arm which, through certain electrical means hereinafter to be described, will eject the ball violently back toward the pitcher. A switch, operated by the weight of the ball, acts to start the operation of the ball return mechanism which, in turn, sets off the operation of a motor which operates certain switches in consecutive order to first move forwardly a resetting arm, secondly starts the motor which will operate certain other switches which, in turn, operate a motor to actuate a reset arm which moves the throwing arm back to normal position and, finally a switch which will release a latching mechanism to free the throwing arm so that it

5 may violently eject a ball which will come to rest by gravity thereon. One of the features of the invention is that while a single ball may be utilized for practice by a pitcher, if the pitcher should desire to use several balls, the same will be held in check by the gateway above referred to and will automatically take their turn in setting up the series of actions which will eventually act to return the same automatically to the pitcher.

10 It is accordingly an object of the invention to provide an apparatus of the character set forth which is comparatively simple in construction, relatively inexpensive to manufacture and yet effective and efficient in use.

15 Another object of the invention is to provide an apparatus of the character set forth having a novel throwing arm forming a part of the invention.

20 Still another object of the invention is the provision, in an apparatus of the character set forth of a novel timing apparatus forming a part of the invention.

25 Still another object of the invention is the provision, in an apparatus of the character set forth, of novel switches forming a part of the invention.

30 Still another object of the invention is the provision, in an apparatus of the character set forth, of novel ball guide means forming a part of the invention.

35 A further object of the invention is the provision, in an apparatus of the character set forth, of a novel resetting arm forming a part of the invention.

40 Another and further object of the invention is the provision, in a device of the character set forth, of a novel gate forming a part of the invention.

45 Other and further objects of the invention will become apparent from a reading of the following specification taken in conjunction with the drawings, in which:

Figure 1 is a front elevational view of a completely assembled apparatus constructed in accordance with the teachings of the present invention.

45 Figure 2 is a reduced sectional view taken along line 2—2 of Figure 1.

50 Figure 3 is a schematic view illustrating certain electrical circuits forming a part of the invention.

55 Figure 4 is a plan view of the device shown in Figures 1 and 2.

Figure 5 is a side elevational view of Figure 4,

Figure 6 is an exploded transverse sectional view, partly in elevation, of a pair of switches forming a part of the invention.

Figure 7 is a fragmentary enlarged plan view illustrating a portion of a throwing arm, its release mechanism and a ball-retaining gate all forming parts of the invention.

Figure 8 is a fragmentary elevational view, partly in section, illustrating certain switches, a throwing arm and allied mechanisms forming a part of the invention.

Figure 9 is a fragmentary plan view of the devices shown in Figure 8.

Figure 10 is a reduced elevational view, partly in section, illustrating the working of a throwing arm forming a part of the invention.

Figure 11 is a fragmentary elevational view illustrating a timing motor and latch mechanism forming a part of the invention.

Figure 12 is a plan view, partly broken away, of the devices illustrated in Figure 11.

Figure 13 is a fragmentary vertical sectional view of the device as illustrated in Figure 12.

Figure 14 is a side elevational view of an actuating bar forming a part of the invention.

Figure 15 is a plan view thereof.

Figure 16 is a plan view of a switch actuating arm forming a part of the invention.

Figure 17 is a side elevational view of Figure 16.

Figure 18 is an enlarged top plan view of an actuating bar forming a part of the invention.

Figure 19 is an enlarged vertical sectional view, partly in elevation, of a throwing arm, ball retaining gate and allied mechanisms forming a part of the invention.

Figure 20 is an elevational view illustrating particularly a latch and release mechanism therefor, both forming parts of the invention, and

Figure 21 is a reduced perspective view of a pick-up device also forming a part of the invention.

Referring more particularly to the drawings, there is shown therein an apparatus of the character set forth wherein is provided a control target having a horizontal base portion 10 and a vertically extending frame 11 both preferably and as shown formed of tubular material. The base 10 is provided with a plurality of supporting wheels 12. Adjustably mounted upon the frame 11 is a platform 13 which is inclined downwardly and rearwardly, as indicated in Figure 2, and downwardly and laterally as shown in Figure 1. A short ball-retaining fence 14 extends upwardly from the sides of the platform 13 with the exception of the lower rear corner portion thereof which communicates with a downwardly inclined runway 15 mounted upon the floor 16 of a ball-returning mechanism which is supplied with supporting rollers 17.

Extending rearwardly from the frame 11 is a plurality of bracket members 18 which support a vertically extending backstop 19 formed of canvas or the like which lies in a plane parallel to the plane of a screen 20 likewise preferably formed of canvas and which is supported by means of lacings 21 connected to the frame 11.

Upon the screen 20 there is marked off, as indicated at 22, a vertically extending rectangular "strike zone" which represents that portion above "home plate" where pitched balls by the pitcher are denoted "strike" by the umpire when a ball passes therethrough. In each corner of the rectangular area 22 there is a cutaway portion 23.

which defines "batter's weakness openings." Centrally in the rectangular area 22 there is defined what may be termed a "warmup zone" 24.

5 A ball pickup device is illustrated in Figure 21 and consists of a frame 25 of tubular material having a forwardly and downwardly extending arm 26 at either side thereof to which arms is affixed by lacings 27 a sheet of canvas 28 or like material. The pickup device is adapted to be positioned upon the ground immediately forwardly of the base 10.

Adjacent the outer end of the runway 15 there is provided a transverse slot 29 in which is vertically swingable a gate 30 (Fig. 19) which is pivotally connected, as indicated at 31, upon a standard 32 which is mounted upon the floor 16. The gate 30 is provided with a relatively short extension 33 beyond the pivotal point 31 and to the outer end of the extension there is connected a tension spring 34 which is also connected with a bracket 35 likewise affixed to the floor 16.

20 A throwing arm 36 is pivotally mounted in a pair of ears 37 which are disposed on opposite sides of a shock absorber housing 38 which is affixed by bolts 39 or the like to the floor 16. The rearward or free end of the throwing arm 36 is provided with a ball-supporting platform 40 having an upwardly extending fence 41 which 30 extends along the outer side thereof and along the rear side thereof.

25 An ear 42 (Fig. 8) is affixed to the throwing arm 36 adjacent the platform 40 but inwardly thereof by means of a bolt 43 or the like and one end of a wire 44 is bent over a bearing 45 mounted upon a shaft 46 carried by the ears 42 and the bent over portion of such wire, indicated at 47, is clamped to the main portion of the wire 44 by means of a clamp 48. The other end of the wire 44 extends over a bearing 49 carried by a shaft 50 in the rear portion of a bracket 51 and its bent over portion, indicated at 52, is clamped to the main portion of the wire 44 by a clamp 53. In the forward end of the bracket 51 there is transversely mounted a shaft 54 having a bearing 55 disposed thereon and to which bearing is affixed one end of a tension spring 56 whose other or forward end is connected to a bracket 57 which is, in turn, affixed by means of a bolt 58 or the like to an upwardly extending forward wall 59 attached at its lower end to the floor 16.

30 A bar 60, shown in detail in Figure 18 of the drawings, extends transversely through the throwing arm 36 adjacent the platform 40 and is held thereto by means of a pair of nuts 61 (Fig. 7). The bar 60 has revolvably mounted thereon a roller 62 against which a reset arm 63 is adapted to bear. The reset arm is connected to a shaft 64 (Figs. 3 and 4) mounted in suitable bearings 65 attached to the floor 16 and its free end extends through a reduction gear box 66 which receives its power from a shaft 67 extending therefrom and which shaft 67 is connected by a coupling 68 with the shaft 69 of a motor 70 likewise mounted upon the floor 16.

35 In Figures 14 and 15 there is illustrated in detail an oscillating switch actuating arm 71 provided with a threaded shank 72 which extends through the throwing arm 36 at a point approximately midway therein and which is fastened thereto by means of a pair of nuts 73 and 74. The outer end of the arm 71 is forked, as indicated at 75, and has revolvably mounted in said 40 forked portion a roller 76. The arm 71 extends

outwardly from the throwing arm 36 in a direction opposite to that of the bar 60.

Extending rearwardly from the forward wall 59 is a vertical panel 77 (Fig. 4) upon which is mounted a normally open contact switch 78 and a normally closed contact switch 79 which switches are illustrated in greater detail in Figure 6.

Referring now to switch 78, it will be seen that there is provided a casing 80 within which is mounted a pair of contact members 81. The casing 80 is provided at its outer side with an opening 82 through which projects a button 83 which is reciprocably mounted upon a shaft 84 surrounding which is a compression spring 85 one end of which bears against the rear of the casing 80 and the other end of which bears against the button 83 to normally hold the same in an outward position. The button 83 is adapted to be contacted by the roller 75 when the same is brought adjacent thereto by means of the throwing arm 36 to thus force a movable contact member 86 carried by the inner side of the button 83 into contact with the fixed contact members 81.

Referring now to the switch 79, it will be seen that the same is provided with a casing 87 having an opening 88 in its forward wall through which projects a button 89 which is slidably mounted upon a shaft 90. Within the housing 87 there is provided a pair of fixed contact members 91 and the shaft has affixed thereto a movable contact member 93 which is normally held against the fixed contact members 91 by a compression spring 94 surrounding the shaft 90 and bearing at one end against the inner side of the casing 87 and at its other end against the inner side of the movable contact 93. The button 89 is provided with a pair of detents 95 which are adapted to move the movable contact member 93 away from the fixed contact members 91 when the roller 76 comes into contact with the button 89.

At 96 (Figs. 3 and 4) is indicated a normally closed contact switch which is adapted to be actuated by an arm 97 carried by the shaft 64 and which arm 97 comes into contact with the switch 96 when the reset arm 63 is in its vertical position. The switch 96 is connected electrically to a relay reversing switch 98 which, in turn, is adapted to reverse the direction of rotation of the motor 79 when the same is started by the switch 78.

Mounted upon the platform 16 is a motor 99 provided with a vertically extending shaft 100. The motor 99 is preferably a small clock type gear motor with a speed of approximately 8 R. P. M. whereas the motor 70 is of a type having approximately one-third horsepower and operating at approximately 1800 R. P. M.

Affixed to the upper end of the shaft 100 (Figs. 11 to 13) is a radially extending arm 101 which is forked, as indicated at 102 at its outer end and within which forked portion there is mounted upon a vertically extending shaft 103 carrying a roller 104.

Forwardly of the motor 99 there is mounted upon the floor 16 a latch casing 105 having an opening 106 in its forward end through which is slidably mounted a latch bolt 107. The bolt 107 is provided interiorly of the casing 105 with an enlarged portion 108 from which projects rearwardly a pair of spaced parallel arms 109 each of which is provided with a laterally extending slot 110 adjacent the rear portion thereof. An arcuate bar 111 extends through each of the slots 110 and has integrally formed therewith a vertically extending shaft 112 which is pivotally mounted in

a bearing 113a formed in the lower portion of the casing 105 and which extends revolvably through the upper side of the casing 105. The shaft 112 has integrally formed at its upper end a rearwardly extending actuating arm 113 which terminates at its rearward end in the path of rotation of the roller 104. The rearward side of the ball holding platform 40 is provided with a rearwardly extending lip 114a which is normally engaged by the bolt 107.

Arranged in circumferentially spaced relation to the motor 99 where they may be contacted by the roller 104 are (see Fig. 3) a normally open contact switch 114, a normally open contact switch 115, a normally closed contact switch 116 and a normally closed contact switch 117. It will be seen that the switches 115 and 116 are closely adjacent to each other and that the actuating arm 113 lies between the switches 116 and 117. The floor 16 also has mounted thereon, in addition to the relay 99, relays 118, 119 and 120.

In operation, it will be apparent that the apparatus may be utilized wherever there is an area sufficiently long to place the apparatus in such position that the target is sixty feet and six inches away from the pitcher desiring to use the same. It will also be apparent that the pitcher may first utilize the warmup target 24 to limber his throwing arm and that thereafter, in order to practice the placing of the thrown ball within the target area 22 but in the corners thereof, he will then attempt to place the ball through the openings 23, it being understood that balls thrown in this area and in such corners are still denoted "strikes" by the umpire when in an actual game. Whether the ball strikes the target 20 or passes through the openings 23, it will still be delivered eventually to the platform 13 due to the fact that the backstop 19 will act to stop the passage of any balls which may have passed through the openings 23. In any event, balls will be delivered by gravity to the platform 13 if they strike either the member 20 or the member 19. Should balls be thrown too low they will be diverted upwardly by means of the device illustrated in Figure 21 since such low balls will strike against the canvas 28 and roll or bounce in an upward direction and eventually be delivered to the platform 13 whence they will roll by gravity to the trough 15 and be held against further movement by means of the gate 30 if the same is in its upward position at the time. If, however, it is in lowered position the ball will continue to travel along the trough 15 in an uninterrupted manner until it hits a switch 121 (Figs. 3, 7 and 19) and it will thereupon continue to roll into the platform 40 where it will be held against further movement by the fence 41. This switch 121 will act to start the motor 99 by means of certain relays as shown in Figure 3. It will be noted that the shaft 100 of the motor 99 revolves in a counterclockwise direction as viewed in Figure 3 of the drawings and that the normal position of the arm 101 and its roller 104 is between the switches 114 and 117. As the motor begins rotating the roller 104 will first come into contact with the switch 114 which will set the relays in condition that when the motor 70 is started by the roller 104 contacting the switch 115, the reset arm 63 will be moved forwardly to allow freedom of movement for the throwing arm 36 when the latter is released. As the arm 101 and its roller 104 continue in their counterclockwise path of rotation to contact the switch 115, the motor 70 will be started and the arm 63 moved forwardly as above stated and it

will be noted that the speed of the movement of the arm 63 is reduced from that of the shaft 69 of the motor through the reduction gearing in the box 66.

Immediately after contacting the switch 115, 5 the roller will come into contact with the switch 116 to thereby stop the motor 70. This stopping is so timed that the motor is deprived of further electrical power prior to the arm 63 reaching its full upward movement and it will be apparent that the remainder of such movement will be due to the inertia of the motion of the various apparatus associated with the motor 70. After contacting the contact member 116, the roller 104 will next come into contact with the actuating arm 113 to move the latch bolt 107 inwardly of the casing 105 thus freeing the lip 114a and allowing the throwing arm to be violently moved in a forward direction to thereby eject the ball toward the pitcher. This violent forward motion of the arm 36 is caused by the action of the tension spring 56 returning to its normal position. At the last portion of such forward movement of the arm 36 a shock absorbing spring 122 which acts between the casing 38 and a cylinder 123 which is carried by the lower end of the arm 36, comes into play to reduce such forward movement and protect the forward wall 59 from violent contact with the arm 36.

It will be apparent that when the roller 104 comes into contact with the actuating arm 113 to thereby move the latch bolt 107 inwardly of the casing 105 that the action that takes place within such casing is such that the arcuate arm 111 is also moved so that a portion thereof lying within one of the slots 110 acts against the rear portion of the leg 109 containing such slots to move the entire mechanism 107-108-109 rearwardly against the action of a tension spring 124 one end of which is connected to an ear 125 upon the forward side of the arcuate arm 111 and the other end of which is connected to the forward side of the casing 105. As the roller 104 passes out of contact with the arm 113, the latter will be returned to its normally rearwardly projecting position due to the action of the tension spring 124 acting to return the arcuate arm 111 to its normal transverse position within the casing 105.

The arm 101 and its roller 104 will then continue on to contact the switch 117 which stops 50 the motor 99 and the motor 99 will remain idle until the ball again contacts the switch 121 to start another cycle as above described.

When the throwing arm 36 is released and pulled forwardly by the action of the spring 56 to substantially a vertical position it will contact through the arm 71 and the roller 76, the switch 78 which will act to start the motor 70. The motor 70 now being reversed through the action of the switch 96 and the vertical position of the setting arm 63, will act to rotate the arm 63 backwardly to its horizontal position. As this occurs the arm 63 will bear against the roller 62 upon the bar 60 to move the throwing arm 36 backwardly to its horizontal position against the 65

action of the spring 56 until the lip 114a is again latched by the bolt 107. During this rearward movement of the arm 36 the roller 76 will eventually come into contact with the switch 79 which will act to stop the motor 70 but at a point slightly before the completed backward movement of the arm 36, it being understood that the remainder of such movement will be due to the "drift" of the motor 70.

While but one form of the invention has been shown and described herein, it will be readily apparent to those skilled in the art that many minor modifications may be made without departing from the spirit of the invention or the scope of the appended claims.

What is claimed is:

1. A pitcher's target of the class described comprising: a target; ball collecting means connected to said target for receiving a ball therefrom; 20 spring actuated ball throwing means disposed to receive a ball from said target received by said ball collecting means; a first electrical contact means actuatable by said received ball; a first electric motor responsive to said first electrical contact means; cyclically operative electrical contact means for causing said first motor to operate through a predetermined cycle of operation; a second electric motor for re-cocking said spring actuated ball throwing means; and a second electrical contact means responsive to said cyclically operative contact means and connected to cause re-cocking operation of said second motor at least once during each cycle of operation of said cyclically operative electrical contact means.

2. A pitcher's target according to claim 1, further comprising a motor reversing contactor connected to said second motor for controlling the direction of rotation thereof for re-cocking said ball throwing means.

3. A pitcher's target according to claim 1 wherein said cyclically operative means comprises a plurality of contact means actuatable to start said second motor to draw said ball throwing means into cocked position, and further comprising mechanically actuatable means responsive to said cyclically operative means for releasing said cocked ball throwing means to throw said ball.

HUGH MULCAHY.
